UNITED STATES PATENT OFFICE

THOMAS H. GAGEN, OF SANDUSKY, OHIO, ASSIGNOR TO THE HINDE & DAUCH PAPER COMPANY, OF SANDUSKY, OHIO, A CORPORATION OF OHIO

CARTON

Application filed June 24, 1929. Serial No. 373,410.

The invention relates to cartons of the type formed of paper or fiber board and has more particular reference to a construction designed for use in shipping fragile articles 5 of a general type but which differ from each other in dimensions. For instance, in the shipment of glass tumblers there are a large number of different sizes and it is usually necessary for the shipper to have a special 10 carton or package for each different size. The present invention provides for the safe shipment of various sizes of such articles in the same carton and requires only the substitution of certain parts which form an insignificant portion of the whole structure. The 15 invention therefore consists in the novel construction as hereinafter set forth.

In the drawings:

Figure 1 is a longitudinal section through 20 a carton of my improved construction;

Figure 2 is a cross section through a portion thereof;

Figure 3 is a plan view of one of the retainer strips;

Figure 4 is a perspective view showing the 25 interior structure of the carton partly broken away.

In the present state of the art cartons formed of single or double faced corrugated 30 paper or fiber board are very extensively used in the shipment of fragile articles such as glassware. To insure safety from impact or jar it is quite usual to provide trays or pads which separate the inner wall of the 35 carton from the outer wall on all sides. It is, however, necessary to provide means for holding the individual articles separate from each other and from movement within the carton which is accomplished by division 40 partitions forming a plurality of separate cells, each of dimensions corresponding to the article to be placed therein. Therefore it is necessary to provide as many different constructions of cells as there are different sizes 45 of articles to be packed therein.

With my improved construction instead of varying the dimensions of the cells I have provided means for holding the individual articles in fixed position within the cells even 50 where the dimensions of the two are very

different, the specific construction being as follows:

The outer carton may be of any suitable construction preferably a rectangular box A formed from a single scored blank of corrugated board folded to form continuous side and end walls and overlapping flaps for bottom and top. Within this outer box is placed an inner structure comprising longitudinal partitions B and cross partitions C each being slotted through substantially one-half its width at suitable points whereby these partitions when engaged will form a series of separate cells. The longitudinal partitions B are of a height corresponding to the sides of the outer receptacle but the cross partitions are of a lesser height to provide space beneath the same for pads or trays D. These trays or pads are supported upon depending side flanges D' and are therefore 70 spaced from the bottom of the outer receptacle.

Instead of making the cellular structure just described in various different sizes to correspond to the dimensions of the articles to be packed, I form a standard construction in which the cells are of a sufficient size to receive articles of maximum dimensions. Thus if the carton is used for the shipment of glass tumblers the cells are of a width which will take a tumbler of maximum diameter and of a height to receive a tumbler of maximum height. Where, however, the carton is used for the shipment of small size tumblers, these are held centrally within each cell by the following construction:

E is a member preferably formed from a sheet of corrugated board which is placed on top of the tray or pad D and which is provided with a series of circular apertures 90 therein corresponding in diameter to the tumblers, preferably the upper end thereof. To hold the tumblers in engagement with this member, a strip F also preferably formed of corrugated board, is engaged with a series 95 of aligned slots in the cross partitions C so as to extend centrally throughout the entire longitudinal series of cells. This strip may be cut to various widths selected to exactly correspond with the distance between the up- 100

per end of the tumblers and the cover of the carton. The slots G in the partitions C in which the strips F are placed are of sufficient distance so as to extend lower than the upper end of the tumblers of the smallest size or height and therefore any strip suitable for engagement with tumblers of any size between maximum and minimum heights may be placed in the same cellular structure.

10 With the construction just described the shipper may keep in stock only the standard size of outer boxes and inner cellular structure, supplemented by apertured strips E corresponding to the various diameters of tumblers and holding down strips F corresponding to various heights of tumblers. These supplementary strips can be made at small cost and occupy very little storage space as compared with the holding in stock of different size cellular structures to correspond to the different sizes of articles to be packed.

What I claim as my invention is:

1. In a carton, the combination with an outer receptacle and an inner structure 25 formed of longitudinal and cross partitions forming a series of separate cells, of a strip extending beneath a series of cells recessed to receive the articles in the individual cells, and a strip engaging registering slots in the 30 partitions between cells, of a width corresponding to the dimension between the top of the outer receptacle and the tops of the articles within the cells to hold said articles in engagement with said recesses.

35 2. In a carton, the combination with an outer receptacle, of an inner structure formed of longitudinal and cross partitions slotted to engage each other and to divide the space into a series of cells, the longitudinal partitions being of a height equal to the height within the outer receptacle and the cross partitions being of lesser height, a supporting tray or pad within the central receptacle extending beneath the cross partitions, a strip 40 above said tray or pad extending longitudinally thereof and apertured to register with the individual cells and to form recesses for engaging the individual articles in said cells, and a strip engaging registering slots in said cross partitions and extending centrally of each of a series of cells, said strip being of a height corresponding to the dimension between the upper end of the individual articles in the cells and the top of the outer receptacle whereby said individual articles are held centrally within their respective cells.

3. In a carton, the combination with an outer receptacle and an inner structure for 45 dividing the same into a series of separate cells, of retaining means comprising a strip extending longitudinally of said carton, apertured to register with the individual cells to form recesses for engaging the individual 55 articles in said cells, and means associated

with said inner structure for maintaining said articles in said recesses.

4. In a carton, the combination with an outer structure and an inner receptacle formed of longitudinal and cross partitions slotted 70 to engage each other and to divide the space into a series of cells, of retaining means comprising means supported longitudinally beneath the cross partitions for engaging the individual articles in said cells, and a vertically arranged strip engaging registering slots in said cross partitions and extending centrally of each of a series of cells, said strip being of a height corresponding to the dimension between the upper end of the individual articles in the cells and under surface of the top of the outer receptacle whereby said individual articles are held centrally within their respective cells.

5. In a carton, the combination with an 85 outer structure and an inner receptacle formed of longitudinal cross partitions slotted to engage each other and to divide the space into a series of cells, of retaining means comprising a vertically arranged strip 90 engaging registering slots in said cross partitions and extending centrally of each of a series of cells, said strip being of a height corresponding to the dimension between the upper end of the individual articles in the 95 cells and the top of the outer receptacle whereby said individual articles are held against the bottom of their respective cells.

In testimony whereof I affix my signature.
